CLAIM

The ornamental design for a vacuum cleaner body, as shown and described.

DESCRIPTION

1. Vacuum cleaner body

1.1 is a perspective view of a vacuum cleaner body showing our new design;

1.2 is a front elevation view thereof;

1.3 is a rear elevation view thereof;

1.4 is a left-side elevation view thereof;

1.5 is a right-side elevation view thereof;

1.6 is a top plan view thereof; and

1.7 is a bottom plan view thereof.

The broken lines in the drawing figures are included for the purpose of illustrating environment and form no part of the claimed design.

1 Claim, 7 Drawing Sheets
